CLAIM

The ornamental design for an on-body injector as shown and described.

DESCRIPTION

FIG. 1 is a perspective view of a new design for an on-body injector having a light source shown in a powered off state, and an activation button shown in a depressed state; FIG. 2 is a front view of the on-body injector of FIG. 1; FIG. 3 is a rear view of the on-body injector of FIG. 1; FIG. 4 is a right-side view of the on-body injector of FIG. 1;

FIG. 5 is a left-side view of the on-body injector of FIG. 1; FIG. 6 is a top view of the on-body injector of FIG. 1; FIG. 7 is a bottom view of the on-body injector of FIG. 1; FIG. 8 is a perspective view of the on-body injector of FIGS. 1-7 showing the light source in the powered off state and the activation button in an undepressed state; and, FIG. 9 is a perspective view of the on-body injector of FIGS. 1-8 showing the light source in the powered on state and the activation button in the depressed state.

The dashed lines are included for the purpose of illustrating environment and form no part of the claimed design.

The stippling shown is included for the purpose of illustrating portions of the claimed design having a visual appearance (e.g., color, texture, glow, etc.) different from the immediately adjacent portions of the claimed design.

The radiating lines are included for the purpose of illustrating a feature of the claimed design in an illuminated state, and form no part of the claimed design.

1 Claim, 6 Drawing Sheets
